UNITED STATES PATENT OFFICE.

JOHN J. O'MARA, OF BROOKLYN, NEW YORK.

CASSEROLE FRAME.

Application filed February 23, 1921. Serial No. 447,148.

To all whom it may concern:

Be it known that I, JOHN J. O'MARA, a citizen of the United States, and a resident of the city of New York, borough of Brooklyn, in the county of Kings and State of New York, have invented a new and Improved Casserole Frame, of which the following is a full, clear, and exact description.

10 This invention relates to a new and improved frame for casseroles, and has for an object the construction of a frame such that the time, labor and expense involved in the manufacture of casserole frames is very substantially reduced.

Another object resides in the provision of a frame and handle portions for casseroles so constructed that the assembling of the parts is such as to permit and facilitate the 20 polishing of the main frame thoroughly before the handle portion is attached, whereby the polishing process is made much more simple.

A further object resides in the provision 25 of a handle portion and a frame portion so related and co-operating as to permit of the quick and ready assembly of a minimum number of parts each of which can be separately formed complete prior to the final 30 assembly of all the parts in their ultimate co-operative relation.

A still further object resides in the particular construction and arrangement of parts which are hereinafter described and 35 claimed and shown in the accompanying drawings.

The invention is shown in the drawings, of which—

Figure 1 is a vertical transverse section 40 taken through the casserole frame on a line passing through the middle of the handle portion;

Figure 2 is a section taken on the line 2—2 of Figure 1; and

45 Figure 3 is a section taken on the line 3—3 of Figure 1.

The preferred embodiment of my invention, as shown in the drawings, comprises a casserole frame in the form of a band 10. It is understood that the material from which this band or frame is formed can be of any suitable design. It is preferable, however, to roll the upper and lower edges of the band or strip as shown at 11, the rolls 50 containing reenforcing or staying wires 12 so as to form beads at the top and bottom

edges and to strengthen the structure, as well as to cause it to retain its shape. The wires 12 may be suitably embedded in the metal in any other manner than that described without departing from the spirit of the invention.

The band, with any appropriate design thereon, is stamped out of a continuous strip of sheet metal, and when the ends thereof are to be connected they are brought into contact as shown at 13 in Figure 2 of the drawings; and if the band is not already provided with openings, such openings are provided adjacent the ends of the connecting parts, as shown at 14.

A handle portion, such as 15, having an integrally formed foot 16, is adapted to be associated with the frame 10 and connected thereto adjacent the seam or connecting line 13 above mentioned. Projecting lugs 17, preferably of some soft metal, extending from the inner faces of the handle and foot portions, are adapted to project through the openings or apertures 14 in the adjacent ends of the band 10 and are flattened over on the inner side of the band to rivet the handle and foot portions to the band or frame.

However, prior to the application of the handle and foot portions to the frame, a sheet-metal plate 18 is placed against the inner face of the frame over the abutting edges and is provided with apertures registering with the apertures 14 in the frame. 90 The edges of these apertures in the plate 18 are turned over, as represented by the numeral 19 in Figure 2, to bind the plate 18 to the frame 10 and hold the adjacent contacting ends of the frame together. By thus providing a plate on the inner face of the frame to hold the ends of the band together, the outside of this band can be polished very readily, since it is firmly and tightly held together without any projecting portions on the outer periphery thereof which is to be polished. After this polishing action has taken place, a similarly-shaped plate 20 is placed over the seam 13 on the outer face of the band or frame 10. This 105 plate may be of any suitable shape, preferably that shown in Figure 3, and the surface of this plate is coated or prepared in a manner similar to that in which the outer surface of the frame and the surfaces of the 110 handle and foot portions are prepared. For instance, this plate 20 may be nickel

plated or silver plated, as desired. The upper end of this plate 20 is provided with a curved lip or ear 21 which is adapted to extend over the upper roll 11 of the frame to hold the plate 20 temporarily in place until the handle and foot portions have been applied, and also to hide the bare end of the seam 13. The plate 20 is provided with apertures designed to register with the apertures 14 in the adjacent ends of the frame 10. When the plate 20 is in place, the handle and foot portions are placed against this plate, with the lug portions 17 projecting through the apertures in the plate 20, the frame 10 and the plate 18, after which the ends of these lug portions are riveted or flattened over on the inside to tightly hold the handle and foot portions and the plate 20 to the frame.

20 It will be readily observed from a consideration of the above description that the handle and foot portions, the plates 20, the plates 18 and the frame 10, can all be completely and separately made and prepared prior to their ultimate assembly. The first step involves the formation of the frame and the connection of its adjacent free ends by means of the plate 18, after which the frame can very readily and simply be polished. The plate 20 can be stamped out and finished and plated complete, as can the handle and foot portions. This capacity of separate manufacture and completion before assembly facilitates the manufacture of the frame and its co-operating parts and also reduces the time, labor and expense involved therein.

What I claim is:

1. A casserole frame comprising a split metallic band having a plurality of apertures adjacent its ends, a metallic plate disposed over the adjacent ends of the band on the inside of the same and provided with openings registering with the openings of the band, a plate arranged over the adjacent ends of the band on the outside of the same, and a handle provided with lugs passing through the apertures of the said band and plates and having their ends flattened on the inner plate.

2. A casserole frame construction comprising a split metallic band having free ends which are placed adjacent each other and which have a plurality of apertures in their

adjacent surfaces, a metallic plate placed over the seams in the adjacent end portions on the outside of the frame and which has apertures registering with the apertures in the frame, a handle portion adapted to be connected to the frame, and projecting lugs on said handle portion, said lugs projecting through the apertures in the plate and frame and riveted on their inner ends to fasten the handle portion, the plate portion and the frame together. 65

3. In a casserole frame, a split metallic band having a plurality of apertures adjacent its ends, and a metallic plate arranged over the adjacent ends of the band on the inner face thereof and having apertures 70 registering with the apertures of the band, the edges of the apertures of the said plate being bent into the apertures of the band to temporarily hold the ends of the band together to permit the outer surface of the 75 band to be polished before the completion of the frame.

4. A casserole frame comprising a split metallic band formed in the shape of a ring having free ends abutting each other, said free ends having a plurality of apertures in their adjacent surfaces, a metallic plate covering the seam and the adjacent ends and disposed on the outside surface of the frame, said plate having apertures registering, when the plate is in position, with the apertures in the frame, a handle portion connected to the frame, projecting lugs on said handle portion, said lugs projecting through the apertures in the plate and frame and 85 riveted on their inner ends to fasten the handle portion, the plate portion and the frame together, and a curved, integral finger portion extending from one edge of the plate over the adjacent edge of the frame 90 to hold the plate to the frame.

5. A casserole frame, comprising a split metallic band having apertures adjacent its ends, metallic apertured plates over the adjacent ends of the band, one on the inside and the other on the outside, the edges of the apertures of the inner plate being bent into the apertures of the band to temporarily fasten said plate to the band, and a handle provided with lugs extending 105 through the apertures of the plates and band and flattened on the said inner plate.

JOHN J. O'MARA.
